UNITED STATES PATENT OFFICE

POMPILIO VALERIO, OF CINCINNATI, OHIO

DESIGN FOR A SPOOL HOLDER FOR SPOOLS OF THREAD AND THE LIKE

Application filed June 5, 1931. Serial No. 40,089. Term of patent 14 years.

To all whom it may concern:

Be it known that I, POMPILIO VALERIO, a citizen of the United States, residing in Cincinnati, in the county of Hamilton and State of Ohio, have invented a new, original, and ornamental Design for Spool Holders for Spools of Thread and the like, of which the following is a specification, reference being had to the accompanying drawings, forming part thereof, in which—

Fig. 1 is a perspective view of a spool holder showing my new design.

Fig. 2 is a plan view of the same.

Fig. 3 is an edge view of the same with the post partly broken away; and,

Fig. 4 is a front view of the same with the post partly broken away.

I claim:

The ornamental design for a spool holder for spools of thread and the like, substantially as shown and described.

POMPILIO VALERIO.
